UNITED STATES PATENT OFFICE.

WILLIAM A. TURBAYNE, OF BUFFALO, NEW YORK, ASSIGNOR, BY MESNE ASSIGNMENTS, TO U. S. LIGHT & HEAT CORPORATION, OF NIAGARA FALLS, NEW YORK, A CORPORATION OF NEW YORK.

TAPERING-CHARGE REGULATOR.

1,197,162.

Specification of Letters Patent. Patented Sept. 5, 1916.

Application filed January 15, 1912, Serial No. 671,297. Renewed July 28, 1916. Serial No. 111,962.

To all whom it may concern:

Be it known that I, WILLIAM A. TURBAYNE, a citizen of the United States, residing at Buffalo, in the county of Erie and State of New York, have invented new and useful Improvements in Tapering-Charge Regulators, of which the following is a full, clear, concise, and exact description, reference being had to the accompanying drawing, forming a part of this specification.

My invention relates to automatic electric regulators.

One of the objects of the invention is to provide an improved modified-constant-potential regulator.

Another object is to provide a very sensitive regulator of the vibrating contact type, a high rate of vibration being obtained without the use of auxiliary devices.

Additional objects will be apparent from the more detailed description hereinafter given.

For the purpose of disclosing the invention, I have illustrated one form of my regulator which is shown connected in circuit in a car lighting system. The invention may, of course, be embodied in other forms, and is adapted for use in systems other than car lighting systems.

The views in the drawings are as follows:—

Figure 1 is a diagrammatic representation of the form of regulator referred to showing the same connected in a car lighting system.

Fig. 2 is a diagrammatic representation of certain modified elements of the regulator. Fig. 3 is a diagram of a further modification.

The operation of the preferred form of regulator illustrated will be readily understood by considering it in connection with a car lighting system. Such a system is shown diagrammatically in Fig. 1 and includes a variable speed generator having an armature 1 and shunt field winding 2 with a storage battery 3 and lamp circuit 4 connected across the external circuit 5 in parallel branches.

The regulator proper includes a resistance which is shown connected in series with the shunt field winding of the generator. The resistance is arranged preferably in two sections 6 and 7, each of which is normally short-circuited. The section 6 is normally short-circuited by the abutting contacts 8,

one of which is relatively fixed and the other 55 of which is preferably mounted on and insulated from the upper end of a movable plunger 9 held in uppermost position by means of an adjustable spring 10. The section of resistance 7 is similarly short-circuited by abutting contacts 11, one of which is mounted on the movable plunger 12 held in uppermost position by a spring 13, which is preferably stronger than the spring 10, or which is preferably adjusted to an increased 65 tension, or both.

Each plunger is adapted to be drawn down against the action of its spring by the increased energization of a series connected coil 14 or a shunt connected coil 15, these 70 coils acting accumulatively. The series coils are connected in the external circuit supplied by the generator, in order to respond to fluctuations in the generator current, and are also connected in series with each other. 75 If desired, an adjustable shunt 16 may be connected across the terminals of the coils 14 in order that said coils may be made to respond to any desired pre-determined current values.

The shunt windings 15 are connected across the generator terminals in order to respond to the voltage developed by the generator. When the generator is at rest and the relation of the various parts of the system is as shown in Fig. 1, these voltage responsive windings are connected in parallel with each other and in series with the resistance 17, in their common path. These voltage responsive coils 15 form the predominating magnetizing windings and if acting alone would tend to regulate the generator to maintain the voltage thereof constant. The regulation effected by these windings is due to increased energization thereof and 95 caused by a tendency toward voltage increase of the generator above a pre-determined point, whereupon the plunger 9 is drawn down against the action of the spring 10, which is the weaker of the two springs, 100 thereby opening the short circuit which normally exists around the section of resistance 6. This section is accordingly inserted momentarily in circuit with the generator field winding 2, thereby tending to reduce the 105 voltage and reducing the energization of the coils 15, whereby the spring 10 again causes the short-circuiting of this portion of the

resistance. The cycle of operations just described is repeated at a rapid rate, the plunger 9 vibrating up and down at a rapid rate, being pivotally supported by the arms 5 or levers 18. The increased energization of the other voltage responsive winding 15 is ordinarily insufficient to overcome the greater tension of the spring 13, and accordingly the section of resistance 7 is ordinarily 10 short-circuited. With an increase in the energization of the first winding 15 to a point about sufficient to hold down the plunger 9 continuously against the action of the spring 10, the corresponding increased energization 15 of the other voltage winding 15 would be sufficient to cause it to overcome the pull of its spring 13, whereby a rapid up and down movement or vibration of the plunger 12 would take place, thereby introducing the 20 section of resistance 7 in the circuit for successive short intervals of time, the section of resistance 6 being continuously in circuit under these circumstances.

While I have illustrated and described 25 only two sections of resistance and corresponding short circuiting contacts, it is apparent that the number may be increased to meet varying requirements. It should be noted that the upper terminal of the left-hand voltage coil 15 is connected to the movable contact 8 of the pair of short circuiting contacts for the resistance section 6. The upper terminal of the right-hand voltage coil 15 is connected to the fixed contact 30 11 of the pair of short circuiting contacts for the section of resistance 7. The circuit through these coils may be traced from the positive side of the line through the short circuiting contacts 8, thence to the common junction point 19. From point 19 one branch of the circuit extends directly to the left-hand coil 15. The other branch of the circuit extends to the short circuiting contacts 11 and through these contacts directly to the other coil 15. Said branch 35 circuits reuniting at the point 20 are connected through the resistance 17 to the negative side of the line.

The voltage responsive coils 15 are adapted 40 to respond at such a value as to hold the generator to a voltage sufficient to send the charging current through the battery against its maximum back pressure or C. E. M. F. Such a voltage value, however, 45 would send an abnormal current through the battery during the early stages of the charging period or when the battery was in a depleted condition. In order to limit the value of the current furnished to the 50 storage battery therefor, the series windings 14 are adjusted to respond to such a current value as to properly modify the generator voltage so as to prevent an unduly heavy current from entering the battery. 55 The plunger 9 will be attracted when the

magnetization imparted by both the voltage responsive winding and the current responsive winding exceeds a certain value, and by virtue of the regulating action of the corresponding section of resistance, the effect will be to maintain constant under given conditions, the sum of the magnetizing effects of the two windings. In other words, the effective number of ampere turns around the magnet core will remain 75 substantially constant. This same general statement of operation applies to the other plunger or core 12 and associated windings.

The general operation of the system as a 80 whole will now be described.

Upon the attainment of sufficient speed of armature rotation the generator will build up its voltage rapidly as a shunt machine and when a certain pre-determined voltage value is obtained, the automatic switch 21, 85 the action of which is well understood, will close, thereby connecting the battery and work circuit across the generator terminals. With continued rise in speed of armature rotation an increasing current will flow into 90 the external circuit until that pre-determined value is reached for which the regulator is adjusted to act. When there is a tendency to exceed this value, one or both of the separable contacts will be opened in 95 the manner previously described, thereby causing resistance to be inserted in the generator field circuit of an average value sufficient to maintain normal conditions, these actions being repeated throughout the 100 whole range of speed through which the generator operates.

When the regulator contacts are in short 105 circuited position, the voltage responsive coils 15, as previously stated, will be connected in parallel directly across the generator terminals through the resistance 17. Upon separation of the contacts 8, however, and consequent momentary interposition of the resistance section 6 in the exciting circuit, the left-hand voltage coil 15 will no longer be connected through the contacts 8 but will be instantaneously connected in circuit with the said resistance section 6, and its energization decidedly decreased due to 110 the voltage drop across said resistance section. As a result of this decreased energization, the spring 10 will immediately return the plunger 9 to normal short circuiting position, whereupon the cycle of operations will be repeated at a very rapid rate. The effect of this connection is to modify 115 the vibrations over what they would be if the voltage winding 15 were connected otherwise, the modified vibrations resulting in a greatly increased sensitiveness of regulation. The same effect is produced by the right-hand voltage winding 15 when the plunger 12 is vibrating. It is apparent, therefore, that a very rapid rate of vibra- 120

tion is attained and very sensitive regulation secured without the use of auxiliary apparatus or high speed coils, no additional coils being used over and above those required for the performance of the main regulating functions.

It will be at once apparent that the combined action of the coils 14 and 15 will result in a tapering charge of the battery 3, 10 for the reason that as the battery approaches full charge and the C. E. M. F. rises, the generator will be able to force less current into said battery.

In Fig. 2 I have illustrated a regulator 15 which operates in substantially the same manner as that just described and in which the cores 22 of the regulating windings are stationary, only the armatures 23 being pivoted. The inertia of the moving parts is 20 thereby reduced.

In Fig. 3 I have shown a further modification in which the vibrating armatures have assumed the form of resilient reeds 24 of magnetic material adapted to be drawn 25 down in response to the energization of the regulating windings and also released thereby in the manner previously described, whereby a very rapid rate of vibration is obtained. It is apparent that various other 30 mechanical arrangements are possible which permit the short-circuiting action to take place at a rapid rate.

I do not desire to limit myself to the forms of regulators selected for the purpose of 35 illustrating my invention, nor do I desire to limit myself to the use of the same in a car lighting system. In general I desire to cover broadly suitable equivalent means for accomplishing the desired results as long as such 40 means fall within the scope of the appended claims.

Having thus described my invention, what I claim as new and desire to secure by Letters Patent of the United States is:—

45 1. In combination with a circuit to be regulated, a resistance normally short-circuited adapted to be inserted in said circuit, short-circuiting contacts for said resistance, and a coil for operating said contacts, said coil 50 being connected across said circuit on the side of said resistance and short circuit remote from the source of supply, whereby when said contacts are closed the said coil is subjected to the full voltage of said circuit 55 and when said contacts are open said coil is subjected to the full voltage of the circuit reduced by the drop across said resistance.

60 2. In combination with a generator to be regulated, an automatic electric regulator having a series solenoid, a shunt solenoid, and short-circuiting contacts, one of which is adapted to vibrate at a rapid rate in response to the energization of one or both of said solenoids, said shunt solenoid being connected in 65 series with said contacts and acting to regu-

late said generator for constant voltage, said series solenoid acting to modify the effect of said shunt solenoid in accordance with the load supplied by said generator.

3. In combination, a variable voltage 70 source, means for regulating said source comprising a resistance, a short circuit around said resistance, a vibrating contact controlling said short circuit, and a coil for operating said contact, said coil being connected 75 across the system on the side of said resistance and short circuit remote from said source, whereby when said short circuit is closed, said coil is subjected to the full voltage of said source, and when said short circuit is open, said coil is subjected to the voltage of said source reduced by the drop across said resistance, said elements coöperating to produce a rapid vibration of said contacts to regulate the voltage of said source. 85

4. In a system of electrical regulation, a voltage responsive winding for regulating to a constant value the voltage of the source of electric energy, a current responsive winding for modifying said voltage regulation in accordance with the load conditions of said system, said windings acting through short circuiting contacts, a fixed resistance, one of said contacts vibrating at a rapid rate to open and close a short circuit around said 90 regulating resistance, said voltage winding being connected in series both with said contacts and with said resistance, whereby when said contacts open said resistance becomes effective to reduce the energization of said 95 winding.

5. A system of electrical distribution comprising a variable speed generator having a shunt field winding, a storage battery and translating devices connected across the external circuit of said generator, a regulating resistance adapted to be connected in series 105 with said shunt field winding, separable contacts normally short circuiting said resistance, one of said contacts being adapted to vibrate at a rapid rate to control the mean effective value of said resistance, a current responsive coil and a voltage responsive coil 110 acting cumulatively to cause said vibrations, said current responsive coil being connected in said external circuit and said voltage responsive coil being connected across the same, the connections to said voltage responsive coil including said resistance and 115 said contacts in parallel branches, the energization of said voltage winding being reduced whenever said contacts separate. 120

6. In a car lighting system, a variable speed generator, a shunt field winding therefor, a storage battery and lamps connected across the external circuit of said generator, a regulating resistance adapted to be connected in series with said shunt field winding for regulating purposes, a voltage responsive 125 solenoid connected across the generator ter- 130

1. minals to give a predominating constant potential regulation to the system, whereby said battery will receive a tapered charge, a current responsive solenoid connected in said external circuit to modify the action of said voltage responsive solenoid, whereby the current supplied to said battery is varied in accordance with the condition of the same, said solenoids having a common core adapted to vibrate rapidly in response to the energization of said solenoids, a contact carried by said plunger and coöperating with a relatively fixed contact to maintain a short circuit around said resistance when said solenoids are deenergized, said contacts being adapted to open and close said short circuit at a rapid rate when said plunger vibrates, thereby controlling the effective value of said resistance, said voltage responsive solenoid being connected across the circuit through said vibrating contacts.
2. In a car lighting system, a variable speed generator, a shunt field winding therefor, a storage battery and lamps connected across the external circuit of said generator, a regulating resistance adapted to be connected in series with said shunt field winding for regulating purposes, a voltage responsive solenoid connected across the generator terminals to give a predominating constant potential regulation to the system, whereby said battery will receive a tapered charge, a current responsive solenoid connected in said external circuit to modify the action of said voltage responsive solenoid, whereby the current supplied to said battery is varied in accordance with the condition of the same, said solenoids having a common core adapted to vibrate rapidly in response to the energization of said solenoids, a contact carried by said plunger and coöperating with a relatively fixed contact to maintain a short circuit around said resistance when said solenoids are deenergized, said contacts being adapted to open and close said short circuit at a rapid rate when said plunger vibrates, thereby controlling the effective value of said resistance, said voltage responsive solenoid being connected across the circuit through said vibrating contacts.
3. An automatic electric regulator for a variable-speed shunt-wound generator, comprising a resistance adapted to be connected in series with the shunt field winding of said generator, a short circuit around said resistance, separable contacts in said short circuit, one of which is adapted to vibrate at a rapid rate to open and close said short circuit for regulating purposes, a voltage

responsive solenoid adapted to be connected across the generator terminals to cause said vibrations and thereby maintain the generator voltage within predetermined limits, a current responsive coil adapted to be connected in the external circuit of said generator to modify said vibrations in response to variations in the current supplied by said generator, the circuit connections to said voltage responsive solenoid including said resistance and said contacts in parallel branches, whereby when said contacts separate said resistance becomes effective to decrease the energization of said voltage responsive solenoid, thereby effecting a rapid rate of vibration and an increased sensitivity in the regulation.

4. In combination with a variable-speed shunt-wound generator, a resistance adapted to be inserted in series with the shunt field of said generator, a short circuit around said resistance, a contact controlling said short circuit adapted to rapidly vibrate to control the effectiveness of said resistance, and a coil for vibrating said contact, said coil being connected across the circuit from said generator, on the side of said resistance and short circuit remote from the generator, to provide for rapid vibration of said contact.

5. An automatic electric regulator, comprising a resistance having two sections connected in series, a shunt circuit around each section, and means for rapidly opening and closing each of said shunt circuits, said means including a voltage responsive solenoid connected in series with each of said resistance sections, said voltage responsive windings being normally connected in parallel relation with each other, said means including also a current responsive solenoid associated with each of said voltage responsive solenoids to modify the effect thereof, said current responsive solenoids being connected in series with each other.

6. In combination with a variable voltage source, a resistance divided into sections for regulating said source, a short circuit around each section of said resistance, a contact controlling each short circuit adapted to be rapidly vibrated to control the effectiveness of its resistance, and means for operating each contact, said means comprising a coil connected in series with the source, and a coil connected across the source on the side of its corresponding resistance remote from the source, whereby the effect of said last named coil will be decreased when the short circuit around its resistance is broken, said arrangement providing for a rapid vibration of said contact.

7. In combination, a shunt-wound generator, a resistance for regulating the shunt field thereof, and a winding for controlling

- the value of said resistance, said winding being connected across said generator when the value of said resistance is a minimum, and said winding being connected across 5 said generator through said resistance when said resistance attains a maximum value, whereby the energization of said winding is decreased to a greater extent than the voltage of said generator.
- 10 13. In combination, a variable-speed shunt-wound generator, a resistance adapted to be inserted in series with the shunt field thereof, a short circuit around said resistance, a vibrating contact for rapidly 15 making and breaking said short circuit, and a coil for controlling said contact, said coil being connected across said generator when said resistance is short circuited, and said coil being connected across said generator through said resistance when said short circuit is open, whereby the energization of said coil is decreased to a greater extent than the voltage of said generator. 21

In witness whereof, I have hereunto subscribed my name in the presence of two witnesses. 25
